UNITED STATES PATENT OFFICE.

LAWRENCE M. JUNKIN, OF PITTSBURG, PENNSYLVANIA.

SEAL-LOCK.

SPECIFICATION forming part of Letters Patent No. 253,870, dated February 21, 1882.

Application filed November 17, 1881. (Model.)

To all whom it may concern:

Be it known that I, LAWRENCE M. JUNKIN, of Pittsburgh, in the county of Allegheny and State of Pennsylvania, have invented a new and useful Improvement in Seal-Locks; and I do hereby declare the following to be a full, clear, and exact description thereof.

My invention relates to that class of seal-locks in which the seal is of frangible metal or glass, and is so placed that when locked the seal must be broken before it can be unlocked.

To enable others skilled in the art to make and use my invention, I will now describe it by reference to the accompanying drawings, in which—

Figure 1 is a plan view of the face-plate and hasp. Fig. 2 is a longitudinal section, and Fig. 3 is a side view, of the lock.

Like letters of reference indicate like parts in each.

This lock is especially designed for use on freight-car doors. In the drawings, *a* indicates a part of such a door, the hasp *b* being pivoted thereto at *b'*; and *c* indicates the frame of the door, in which the lock is placed in a hole or mortise, *d*. The lock is formed of three pieces and a spiral spring. The first piece is the barrel *e*, which is round in cross-section, and has a stem, *e'*, of polygonal shape, extending from its lower end, and a thumb-piece or button, *e''*, at its upper end. The second piece is a sliding collar, *f*, placed on the stem *e'*, and held up against the shoulder *e''* of the barrel *e* by the before-mentioned spring *g*, said spring being held in place on the stem by a washer, *h*, which affords a suitable bearing for the lower end of the spring, and in turn rests upon a pin, *e''*. The third piece is the face-plate *i*, having a sleeve or tubular projection, *i'*, which extends down around the barrel *e*. At opposite points on the lower edge of the sleeve *i'* are inclines *i''*, which at their lower ends terminate in notches or recesses *i'''*. In the side of the sleeve *i'* is an inclined slot, *i''*, through which a guide-pin, *e''*, is designed to project from the barrel *e*. On the outside of the sliding collar *f* are two pins, *f'*, which engage the inclines and recesses *i'''*, being forced against them by the pressure of the spring *g*. The lock is se-

cured in the mortise *d* by screws *k* or otherwise.

When it is desired to lock the door the hasp *b*, which has a hole, *b''*, for that purpose, is placed over the barrel of the lock. When the barrel is in its normal position its upper end is flush with the bottom of the recess *b'''* in the hasp. Then a frangible metal or glass seal, *l*, having a center slot, *l'*, to permit it to pass, is placed over the head *e''*. The thickness of the seal is less than the distance between the head *e''* and the top of the barrel *e*, so that when the barrel is turned the lower side of the head will ride up on the edges of the slot *l'*. The seal being in place, the barrel is turned by means of the head or thumb-piece *e''* one-quarter way around, or until the head *e''* stands at right angles to the slot *l'*. This causes the pins *f'* to ride down on the inclines *i''*, compressing the spring *g*, and spring up into the recesses *i'''*. As it is then impossible for the pins *f'* to turn either way, or for the barrel to be rotated until they are pushed down out of the recesses, and as this cannot be done while its seal remains under the head, the hasp is securely locked until the seal is broken and removed. Then the barrel can be pushed down far enough to carry the pins *f'* clear of the recesses *i'''* and permit the barrel to be turned.

It is apparent that the construction of some of the parts may be varied without changing the principle of my improvement—as, for instance, the shank *e'* may be round, with a feather and spline, or any other shape to keep the collar *f* from turning on it. There may be but one incline and recess on the sleeve *i'*, and the guide-slot *i''* and pin *e''* be arranged on the opposite side, or there may be more inclines than two, the purpose being to secure a ratchet movement of the pins, which will force down the collar *f* and compress the spring. When the hasp is in place it covers two of the screws *k*, so that the face-plate cannot be unscrewed and taken off when the hasp is locked.

My improved lock is simple and cheap in construction and efficient in operation.

What I claim as my invention, and desire to secure by Letters Patent, is—

1. The combination, in a seal-lock, of a rotating barrel, a sliding collar having projecting pins mounted on the stem of the barrel so as to turn with it, a spring mounted on the 5 stem between the collar and a stop or pin at the lower end of the stem, and inclines and notches upon which the pins of the collar play, substantially as and for the purpose described.
2. The combination of the headed barrel

having both an axial and longitudinal movement with a recessed hasp and a slotted frangible seal of metal or glass.

In testimony whereof I have hereunto set my hand.

LAWRENCE M. JUNKIN.
